UNITED STATES PATENT OFFICE

DEZ ALBRITTON, OF SPOKANE, WASHINGTON

DESIGN FOR A MEMORANDUM PAPER HOLDER OR SIMILAR ARTICLE

Application filed February 24, 1931. Serial No. 38,812. Term of patent 7 years.

To all whom it may concern:

Be it known that I, DEZ ALBRITTON, a citizen of the United States of America, residing at Spokane, in the county of Spokane and State of Washington, have invented a new, original and ornamental Design for a Memorandum Paper Holder or Similar Article, reference being had to the accompanying drawing, forming a part thereof.

The figure represents a perspective view of the design for a memorandum paper holder or similar article, showing my new design.

I claim:

The ornamental design for a memorandum paper holder or similar article, as shown.

DEZ ALBRITTON.
